UNITED STATES PATENT OFFICE.

LOUISE P. WELCH, OF GULFPORT, FLORIDA.

ARTIFICIAL FLOWER.

1,413,438.

Specification of Letters Patent. Patented Apr. 18, 1922.

Application filed March 10, 1921. Serial No. 451,209.

To all whom it may concern:

Be it known that I, LOUISE P. WELCH, a citizen of the United States, residing at Gulfport, in the county of Pinellas and State of Florida, have invented certain new and useful Improvements in Artificial Flowers; and I do hereby declare the following to be a full, clear, and exact description of the invention, such as will enable others skilled in the art to which it appertains to make and use the same.

The object of the invention is to provide attractive, relatively inexpensive and durable artificial flowers, suitable for artistic purposes, for trimming hats or bonnets and for other ornamental purposes, and an inexpensive method of producing the same from a foundation material of relatively negligible cost which is susceptible of being molded or formed to produce an unlimited variety of shapes and of permanently retaining such shapes while affording a sufficient resilience or yielding quality to avoid breakage incident to the use of such objects in connection with hats and like wearing apparel; and with this object in view the invention consists in a construction and combination of which a preferred embodiment is illustrated in the drawing, wherein:

Figure 1 is a view of a typical batch of artificial flowers constructed in accordance with the invention.

Figure 2 is a view of the conch spawn as removed from the shell.

The foundation material of the improved artificial flowers consists of the gelatinous substance constituting the spawn of the conch and usually found in conch shells, the same occurring, as indicated in Figure 2, in a form resembling a connected series or string of bulb-like leaves or cells which while flexible when moistened, are of a peculiar toughness of fibre and are susceptible of being molded or shaped by means of dies or the equivalent thereof to resemble the leaves and petals

of flowers or complete flowers and which are readily absorbent of liquid dyes of either aniline, metallic or mineral derivation and retain the dye indefinitely without any apparent deterioration of the structure of the base. After being dyed and suitably dried in the form into which the material has been pressed or shaped to represent flowers or petals or leaves thereof, the shape is retained while there is a sufficient flexibility of the material to avoid any tendency to brittleness or breakage, so that the article is peculiarly adapted for use in the production of artificial flowers such as are worn upon hats or bonnets and which in the ordinary use are subjected to more or less jarring or vibration which would tend to cause a more brittle material to break and lose its identity and attractive appearance.

Obviously by variation of the dies used in the forming of the blanks from the spawn cells and a variety in the use of colors of the dyeing materials employed, an unlimited number of designs may be produced in simulation of any of the natural flowers and even fruits such as are employed in connection with hats and other ornamentations.

Having thus described the invention, what I claim is:—

1. A new article of manufacture consisting of the cells of conch spawn shaped in the simulation of flowers. 75

2. As a new article of manufacture, an ornament which is a simulation of a natural article and which has its constituent parts made up of conch spawn cells shaped in simulation of the constituent parts of the simulated article. 80

In testimony whereof I affix my signature in presence of two witnesses.

LOUISE P. WELCH.

Witnesses:

Mrs. J. TURNER,
NATHAN B. MCKINNEY.
